JOSEPH SACHS, OF HARTFORD, CONNECTICUT, ASSIGNEE, BY MESNE ASSIGNMENTS, TO
THE HART & HEGERMAN MANUFACTURING COMPANY, OF HARTFORD, CONNECTICUT,
A CORPORATION OF CONNECTICUT.

PLUG AND SOCKET CONNECTOR.

1,220,993.

Specification of Letters Patent. Patented Mar. 27, 1917.

Original application filed August 30, 1912, Serial No. 717,942. Divided and this application filed March 13, 1915, Serial No. 14,240. Renewed February 26, 1917. Serial No. 151,152.

To all whom it may concern:

Be it known that I, JOSEPH SACHS, a citizen of the United States, residing at Hartford, in the county of Hartford and State 5 of Connecticut, have invented certain new and useful Improvements in Plug and Socket Connectors, of which the following is a specification.

This invention relates to plug and socket devices, the object of the invention being to 10 provide an article of this character which has effective means for rapidly insuring a firm, substantial contact between the metal shell of the plug and the metal shell of the 15 socket.

In the accompanying drawing forming a part of the present specification, I have 20 illustrated in section one of the several forms of embodiment of the invention, 25 which will be set forth in detail in the following description. I do not restrict myself to this disclosure; I may depart therefrom in several respects within the scope of the invention defined by the claims following 30 said description. The device involves in its make-up a plug member as 2 and a socket or receiving member 3.

The plug member has a body or core as 35 of some suitable material such as porcelain, 40 being generally of approximately cylindrical form. This body or core 4 is surrounded by the metal shell 5 constituting a suitable contact and which as shown is externally 45 threaded to engage internal threads in a shell carried by the socket member or receptacle 3 as will hereinafter more particularly appear. The lower or inner end of the shell 5 extends short of the corresponding end of the core 4. The upper end of 50 said shell 5 has an inturned flange 6 which as shown is integral with the shell and which finds a bearing or seat upon the flat top portion of the cavity 7 in the ring 8, the latter being of some suitable material such as 55 porcelain. The flange 5 is provided with an upwardly projecting tubular portion 9 which is disposed in the central opening of the insulating securing ring 8. Said tubular portion or extension 9 of the shell 5 is 60 threaded upon the boss 10 of the bushing 11 which externally fits flatwise against the

ring 8. The bushing 11 is hollow and as shown is also of insulating material, such as molded material. The core 4, the shell 5, the ring 8 and the bushing 11, therefore, 55 constitute a unit.

Inclosed by the contact shell 5 is a wire connector 12 of metal and which in the present case has both a mechanical and an electrical connection with said shell. The mechanical connection can be obtained by riveting or otherwise suitably securing the butt of the connector to the shell; the engagement between the two parts provides for the electrical connection. This connector 12 has 60 a threaded hole to receive the screw 13, the head of which is located opposite an opening 14 in the side of the shell 5 to provide access to the screw 13 exteriorly of said shell for the connection of a wire to the connector 65 12 or its disconnection therefrom. The connector proper or the body thereof is situated in the external longitudinally disposed recess 15, while the inner end of the screw is located in a channel 16 opening into said 70 recess to thus provide a double key connection between the shell 5 and the core 4 and as a consequence effectually prevent relative rotation of said shell and core. One wire of 75 an extension cable can be passed through the opening of the hollow plug 11 through the open upper side of the body or core 4 and wrapped one or more times around the screw 13 between the head thereof and the body of the connector 12. The other wire 80 can be passed through the opening 17 of the core through the eyelet 18 in the bottom thereof and passed around the screw 19. Said screw is threaded into the metal plate 85 20 fitted in the recess 21 in the bottom of the core 4, the wire being clamped against said plate by the screw 19, the head of which for this purpose forces the washer 22 against said wire. The screw 19 extends through the cup-like washer or disk 22 which acts as 90 a suitable central end contact for the plug member 2. The eyelet may as shown pass through an opening in and be headed over the plate 20.

The socket or receptacle member also 95 comprises a body such as 23 of some suitable insulating material as porcelain. Said body

has a chamber as 24 open in the top and intended to receive the contact shell 25 into which is insertible the contact shell 5 of the plug member 2. Within the shell 25 is a central contact 26 engageable by the central end contact or washer 22 of said plug member when the latter has bottomed in the socket or receptacle member 3, the central contact 26 and the shell 25 being as usual insulated from each other. The contact shell 25 is contractible, both it and the plug contact shell 5 being generally made of sheet metal. As represented the contact shell 25 is longitudinally slit as at 27 at 10 one or more places to increase the resiliency thereof of said shell 25. The slits 27 as represented extend from the upper edge almost to the inturned flanged end of said shell 25, the inturned flange 28 of which is adapted 15 to receive screws as 29 constituting a convenient means for holding said shell in position. The upper end of said shell 25 is provided with an external flange 30 on a downward outward taper to thus produce 20 an external cone surface to coöperate with the operating cone surface 31 on the plug member. Said cone surface 31 as shown constitutes the side wall of the cavity 7 the two cone or taper portions being practically 25 upon the same angle. Just before the plug member 2 bottoms in the socket or receptacle member 3, the cone surface 31 will engage the cone surface of the flange 30, so that on the further rotary movement of the plug member, the cone surface 31 by acting 30 against the cone surface of the flange 30 will constrict the shell 25 into substantial engagement with the shell 5, the maximum contact being obtained when the plug member has been fully bottomed. It will be noted that the side portion of the shell 25 is spaced or separated from the side wall of the chamber 24 to thus insure proper action of the shell 25. The upper end of the 35 chamber 24 is shown somewhat enlarged so as to provide for the free entrance of the confining ring 8 into said chamber 24.

The present case is one of two divisional 40 applications of my application Serial No. 50 717,942, filed August 30, 1912. In the first or other of said two divisional applications, of which the present case is one, I have shown, described and claimed a contact shell as 5 having an opening as 14 to provide 45 ready access to a connector as 12.

What I claim is:

1. An electrical socket member comprising an insulating body, a contact shell inclosed by the body, and a contact also inclosed by said body, a plug provided with a contact shell insertible into said other contact shell and also provided with a contact to coöperate with the contact in the body, said plug having means to contract the first 55 contact shell onto the second contact shell.

2. In a plug and socket device a receiving contact shell, a plug member insertible in said receiving contact shell, and means on the receiving contact shell and the insertible plug member whereupon by the insertion of the plug into the receiving contact shell the latter is contracted upon the plug.

3. An electrical plug and socket device comprising a socket member having an interior contact shell, a plug member provided with a shell insertible in the other shell, the plug member being provided with means to engage the shell of the socket member to contract the same into engagement with the shell of the plug member.

4. An electrical socket member comprising an insulating body, a contact shell in the body, and a second contact also inclosed by the body, said shell being contractible and having an external flange at the free end thereof, provided with a cone surface combined with a plug member comprising a contact shell and a contact, the shell of the plug member being insertible in the other contact shell and the plug member being provided with means to engage the cone surface to contract the first mentioned contact shell on the second mentioned contact shell.

5. An electrical plug and socket device comprising a socket having a contact shell, and a contact independent of the shell, a plug member provided with a contact shell to coöperate with the other contact shell and also provided with a contact to coöperate with said other contact, said plug member having means for contracting the first mentioned contact shell on the second contact shell on relative movement of the two members.

6. A plug and socket device comprising a socket member having an interior internally threaded contractible contact shell fastened therein and also having a central contact mounted therein, and a plug member having an externally threaded contact shell to engage with the threads on the other shell to connect the two members, the plug member being provided with means for contracting the shell of the socket member onto the shell of the plug member on relative movement of the two members.

7. An electrical plug and socket device comprising a socket member having an interior contact shell, a plug member provided with a shell insertible in the other shell, the plug member having an insulating portion and said insulating portion being provided with means to engage the shell of the socket member and contract the same into engagement with the shell of the plug member.

8. An electrical plug and socket device comprising a socket member and a plug member insertible into the socket member, the socket member having an insulating

body provided with a contact shell therein and the plug member having a core, and a contact shell surrounding the core and insertible into the other shell, said plug member also having a cone portion to engage the shell in the socket member and contract the same upon the shell of the plug member on relative motion of the two members.

9. An electrical plug and socket connecting device comprising a socket member and a plug member insertible into the socket member, the socket member comprising an insulating body provided with an interior contact shell slit to produce tongues and provided with an external conical flange, the plug member comprising an insulating core, and a shell surrounding the same insertible into the other shell, the plug member having an insulating portion provided 20 with a conical surface to engage said flange and contract the shell of the socket member onto the shell of the plug member.

10. An electrical plug and socket device comprising a socket member having an interior contact shell, a plug member comprising an insulating core, a contact shell surrounding the core, a ring inclosing the shell, the shell having a tubular portion extending into the opening of the ring, and the plug 30 having a bearing against the ring and connected with said tubular portion, the shell

of the plug member being insertible into the shell of the socket member, and the insulating part of the plug member being provided with means for contracting the shell of the socket member onto the shell of the plug member. 35

11. An electrical plug member comprising an insulating core, a shell surrounding the core provided at its upper end with an inturned flange furnished with an upwardly projecting tubular threaded extension, a ring around the shell, the opening of the ring receiving said extension and the ring having a cavity to receive the shell and to 40 provide a bearing therefor, and a plug in threaded engagement with said extension and bearing against the ring, the side of the cavity being conical, combined with a socket member comprising a contact shell to receive said other shell, the conical surface of said cavity being adapted to engage the free portion of the contact shell of the socket member to contract the same on the shell of the plug member. 50

In testimony whereof I affix my signature in presence of two witnesses.

JOSEPH SACHS.
